ATTACHMENT FOR SEWING MACHINES

Robert Cunning, Endicott, N. Y.

Application October 9, 1937, Serial No. 168,288

2 Claims. (Cl. 112—45)

This invention relates to attachments for sewing machines and more particularly to attachments adapted for use with a sewing machine utilized in the manufacture of leather goods.

5 One object of this invention is the provision of an improved foot adapted to be utilized with a sewing machine of the type used in making shoes.

A further object is the provision of a foot for a sewing machine having a blade associated therewith adapted to cut the material being sewed simultaneously with the sewing thereof.

10 An additional object is the provision of such a blade so arranged that the same may be readily removed or replaced.

15 A further and more specific object is the provision of such a blade which may be positioned with respect to the foot to provide a cut of variable depth.

A further and more specific object is the provision of a sewing machine foot having a blade associated therewith particularly adapted to be utilized in sewing and cutting a groove, to simulate, in one piece of leather, a toe piece and a top piece for moccasins.

20 As conducive to a clearer understanding of the objects of this invention it should be pointed out that in a moccasin type shoe the toe is comprised of two portions, a toe piece adjacent the last and a top piece secured thereto. For various reasons such as economy in manufacture, it is sometimes desirable that the two members required to form the standard design for this type of shoe be formed of one integral piece of leather. In such cases a double line of stitching is usually provided along 25 that portion of the piece where the seam would be positioned were two separate pieces of leather utilized.

30 Subsequent to this stitching operation a cut has hitherto been made in the leather between the two lines of stitching in order to simulate the appearance of two separate pieces of leather. Prior to applicant's invention this cut has been made as a separate operation and customarily by hand.

35 It is an object of this invention, therefore, to provide a mechanism which will perform the above described cutting operation simultaneously with the stitching operation thereby saving time and labor.

40 Other objects will in part be obvious and in part be pointed out hereinafter.

The invention accordingly consists in the combinations of parts, arrangements of elements and features of construction all as will be more fully

pointed out hereinafter and shown in the accompanying drawing wherein:

Figure 1 is a side elevational view of one form of the inventive concept disclosing the same attached to a presser foot bar of a sewing machine, 5

Figure 2 is a front elevational view of the device shown in Figure 1 as viewed from the right,

Figure 3 is a sectional view of the device taken along the line 3—3 of Figure 1 as viewed from the top,

Figure 4 is a bottom plan view taken substantially along the line 4—4 of Figure 1, and

Figure 5 is a detailed view showing one of the elements comprising a portion of the invention.

Similar reference characters denote similar 15 parts throughout the several views of the drawing.

Having particular reference now to the drawing, there is generally indicated at 10 a sewing machine foot comprised of shank 11 and a foot 20 portion 12.

Shank 11 is provided with an aperture 12 which may be suitably threaded to accommodate a set screw 13 or other analogous securing means for securing the same to a suitable presser foot bar 25 14, which may also be provided with a threaded recess to engage the threaded portion of set screw 13. Thus the presser foot may be readily attached to or removed from the sewing machine as desired.

Foot portion 12 comprises a block of relatively substantial thickness provided at its upper extremity with a slot 13 extending the full length thereof.

Slot 13 broadens into a groove 14 adjacent the 35 base of the foot (see Figure 2) which groove, is provided with cutaway portions 15 adjacent one end thereof, the purpose of which portions will be more fully described hereinafter.

A blade 16 is positioned in slot 13 and held 40 therein as by set screws 17 which engage suitable threaded recesses in foot 12, as better shown in Figure 5, blade 16 comprises an extending portion 20 substantially the length of slot 13 and is provided with notches 21 positioned for coaction 45 with screws 17. A cutting edge 22 projects downwardly from slot 13 into groove 14. Thus it will be seen that tightening of set screws 17 compresses the sides of slot 13 against blade 16 to hold the same in related assembly with slot 13 50 and that, due to the configuration of notches 21 the blade may be moved upwardly or downwardly to vary the position of cutting edge 22 within groove 14. It will additionally be seen that by releasing set screws 17 blade 16 may be readily 55

removed for replacement or sharpening or other desired purposes without extensive disassembly of the device.

5 An aperture 25 extends completely through foot 12 on opposite sides of blade 16 and is designed to have passed therethrough a pair of needles 26, one of which operates on either side of blade 16.

10 Now from the foregoing it will be seen that as a moccasin toe comprising a single piece of leather is fed into foot 12 from the left, as viewed in Figure 1, cutaway portions 15 compress a portion of the leather to form a ridge therein. Needles 26, operated in any desired conventional manner, form a line of stitching on each side of the ridge thus formed and cutting edge 22 of blade 16 simultaneously forms a cut of variable depth, depending on the positioning thereof, in the ridge of leather between the rows of stitching, thus simulating a two piece moccasin toe in one simple, rapid and efficient operation.

15 It will therefore be seen that there is herein provided a structure which accomplishes the objects of this invention, and others, including many 20 advantages of great practical utility.

25 As many embodiments may be made of this invention, and as many modifications may be made in the embodiment of the invention herein set forth, it is to be understood that all matter hereinbefore described or shown in the accompany-

ing drawing is to be interpreted merely as illustrative and not in a limiting sense.

I claim as my invention:

1. In combination with a sewing machine having means for forming a double row of stitching, 5 a foot, means associated with said foot for forming a ridge in the material to be stitched and means associated with said foot for forming a cut in the stitched material in said ridge between said rows of stitching, said last mentioned means comprising a blade having notches therein carried by said foot and positioned between the paths of movement of said means for forming said double row of stitching and means for ready replacement of said blade, said last mentioned 10 means comprising releasable set screws mounted in said foot and engaging said notches in said blade.

15 2. An attachment for sewing machines comprising, in combination, a foot, means for securing 20 said foot to said sewing machine, a groove in said foot, a removable blade secured in said groove, and means associated with said groove for forming a ridge in the material to be stitched and forcing said ridge against said blade, said 25 last mentioned means comprising cutaway guide portions in said groove adjacent that end of said groove into which said material is fed.

ROBERT CUNNING. 30
